LAPEL TEMPLATE FOR POSITIONING MILITARY INSIGNIA

Joseph De Grazia, 5110 41st St. NW., Washington, D.C.

Filed Sept. 1, 1960, Ser. No. 61,960

Term of patent 14 years

(Cl. D29—2)

The broken line showings are for illustrative purposes only.

The invention described herein, may be manufactured and used by or for the Government for governmental purposes, without the payment to me of any royalty thereon.

I claim:

The ornamental design for a lapel template for positioning military insignia, substantially as shown and described.
